UNITED STATES PATENT OFFICE.

CALVIN ELDER, OF ST. JOSEPH, MISSOURI, ASSIGNOR TO MARY M. ELDER, OF ST. JOSEPH, MISSOURI.

TRAFFIC SIGNAL.

Application filed February 14, 1925. Serial No. 9,224.

To all whom it may concern:

Be it known that I, CALVIN ELDER, a citizen of the United States, residing at St. Joseph, in the county of Buchanan, State of Missouri, have invented certain new and useful Improvements in Traffic Signals, of which the following is a specification.

This invention relates to an improvement in traffic signals especially designed for use on automobiles, trucks, or other vehicles.

The invention aims to provide a traffic signal of this character which is of simple and durable construction and easy and comparatively inexpensive to manufacture and install and which when in use affords a striking indication of changes in the rate or direction of motion which the driver of the automobile on which the signal is mounted intends to make, the signal being especially designed to give a clear and unmistakable indication of the intention of the driver of the car to come to a stop or to make a right or left hand turn.

Other objects and advantages reside in certain novel features of the construction, arrangement and combination of parts which will be hereinafter more fully described and particularly pointed out in the appended claim, reference being had to the accompanying drawings forming a part of this specification, and in which:—

Figure 1 is a perspective view of one form of the invention,

Figure 2 is a view in section showing the structure of the semaphore signal arm,

Figure 3 is a fragmentary view partly in section and partly in elevation showing the mounting of the semaphore illustrated in Figure 1,

Figure 4 is a fragmentary perspective view showing a slightly different form of signal mounting and operating means,

Figure 5 is a view in horizontal section of the arrangement shown in Figure 4, and

Figure 6 is a perspective view showing another form of mounting for the signal.

Referring to the drawings and more especially to Figures 1 to 3, the numeral 1 designates the post of a closed car structure.

In an opening provided in the post 1 a bearing sleeve 2 is fitted and has its ends projecting beyond the post. On the projecting ends of the sleeve 2 collars 3 are fitted and suitably secured. A shaft 4 is rotatably fitted in the sleeve 2. Adjacent its outer end the

shaft 4 is provided with a squared portion 5 and on this squared portion 5 a semaphore 6 is mounted, the semaphore having a squared opening snugly receiving the squared portion 5 of the shaft so that the semaphore is constrained to partake of the rotary motion of the shaft. A nut 7 is threadedly engaged with the extreme end of the shaft 4 beyond the squared portion 5 and prevents the semaphore from slipping over the end of the shaft.

The semaphore 6 is frictionally engaged with one of the collars 3 by virtue of the action of a coil spring 8 which encircles the shaft 4 and which has one end engaged with a collar 3 and the other end engaged with an adjustable collar 9 held on the shaft 4 by a set screw 10.

A crank handle 11 is provided and has a hub 12 slidably fitted on the shaft 4 and held in adjusted position by a set screw 13. The adjustable mounting of the crank handle on the shaft 4 enables the signal to be adapted to the reach of the operator.

The semaphore 6 includes a body made of cast metal such as alumina or the like or it may be constituted of pressed iron or any other suitable material. Openings 14 are provided in the sides of the body and in these openings panes of glass, designated 15, are mounted. These panes of glass are translucent but may be colored or frosted if found desirable. As indicated at 16 the body of the semaphore is made heavier adjacent the mounting of the body on the squared portion 5 of the shaft 4 and in this heavy portion an opening 17 is provided to receive a light socket 18. The light socket 18 is designed to receive an electric light bulb 19 and this socket carries a reflector 20 which is of such a character as to reflect the light throughout the semaphore whereby both panes 15 are illuminated. Electric light wires 21 extend through an opening 22 provided in the semaphore 6 and through an opening 23 provided in the shaft 4.

These wires are embodied in a suitable lighting circuit which, of course, may include a suitable switch.

In the form of the invention shown in Figures 4 and 5 a semaphore 6 identical with that just described is mounted on a shaft 25 which extends fore and aft of the vehicle through a bearing sleeve 27 in a post 26. A worm wheel 28 is fixed to the

shaft 25 and is actuated from the worm 29 carried by a crank shaft 30 which is rotatably mounted in a bearing 31 fixed to the post 26.

5 Figure 6 illustrates that the bearing sleeve 2 of Figures 1 to 3 may be provided with a clamp, designated generally at 35, and includes a pair of jaws 36 controlled by a clamping bolt 37 and a nut 38. The arrangement shown in Figure 6 is intended for use on open cars where a windshield frame or other structure adapted to be clamped is available. Of course, the shaft, 10 semaphore, handle and spring are associated with the bearing sleeve as before.

15 With the signal constituting the present invention an attractive and useful automobile accessory is provided. The signal arm is illuminated and is clearly visible at night as well as in the day. It is not necessary to have the windows of the car open to make 20

the required signals and the signal afforded is striking and clear. The operator may easily actuate the signal through all of its signalling movements and in the form of 25 the invention shown in Figures 1 to 3 the semaphore is held in any adjusted position.

I claim:

In a traffic signal adapted to be supported on a post, a bearing sleeve adapted to be 30 mounted on the post, collars fitted on the end of the sleeve and adapted to engage the post, a shaft rotatably fitted in the bearing sleeve, a semaphore fixed on one end of the shaft and engageable with one of the collars, 35 a coil spring having one end engageable within the collar, a collar fixed on the shaft and engaging the other end of the coil spring, and a handle independent of the collar and adjustably fixed on the shaft 40 and turning the same.

CALVIN ELDER.
